UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A SIFTER-TOP CAN OR SIMILAR RECEPTACLE.

54,383.

Specification for Design.

Patented Feb. 10, 1920.

Application filed July 3, 1919. Serial No. 308,668. Term of patent 7 years.

To all whom it may concern:

Be it known that I, MARTHA HALOWELL CONNOR, a citizen of the United States, residing in the city of Baltimore, State of Maryland, have invented a new, original, and ornamental Design for a Sifter-Top Can or Similar Receptacle, of which the following is a specification, reference being had to the accompanying drawing, forming a part thereof, wherein—

Figure 1, is a view in elevation of a sifter top can embodying my design,

Fig. 2, is a top plan view thereof,

Fig. 3, is a cross sectional view on the line 3—3 of Fig. 1.

What I claim is:

The ornamental design for a sifter top can or similar receptacle, as shown.

MARTHA HALOWELL CONNOR.
